OTHER PUBLICATIONS

Illustration of a lunch container sold at least as early as Oct. 14, 2011.

Primary Examiner — Susan Bennett Hattan*Assistant Examiner* — Shannon Morgan(74) *Attorney, Agent, or Firm* — Davis Wright Tremaine LLP; George C. Rondeau, Jr.(57) **CLAIM**

The ornamental design for a food container, as shown and described.

DESCRIPTION

FIG. 1 is a top, right side perspective view of a food container showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines represent portions of the food container that form no part of the claim.

1 Claim, 5 Drawing Sheets(56)
